(57) **CLAIM**

The ornamental design for a massager head for a fascia gun, as shown and described.

DESCRIPTION

Figure 1.1 is a front view of a massager head for a fascia gun showing our new design;

Figure 1.2 is a back view thereof;

Figure 1.3 is a left view thereof;

Figure 1.4 is a right view thereof;

Figure 1.5 is a top view thereof;

Figure 1.6 is a bottom view thereof; and

Figure 1.7 is a perspective view thereof.
